UNITED STATES PATENT OFFICE.

FREDERICK J. SHEPARD, JR., OF AUBURNDALE, MASSACHUSETTS, ASSIGNOR TO LEWIS-SHEPARD COMPANY, OF WATERTOWN, MASSACHUSETTS, A CORPORATION OF MASSACHUSETTS.

ELEVATING TRUCK.

Application filed May 3, 1923. Serial No. 106,364.

This invention relates to improvements in elevating trucks of the type in which the load supporting means is elevated by suitable mechanism and the descent of the load controlled by cushioning means, such as a dash pot. In usual trucks of this character the load supporting means is raised by mechanism operable, preferably but not necessarily, step by step, by the vertical swinging movements of the tongue of the truck, the load supporting means with the load thereupon being locked in elevated position, while the truck is transported to its destination, the locking mechanism then released and the descent of the load cushioned by the dash pot. The release of the locking mechanism is usually accomplished by forcibly disengaging the locking device so that the load supporting means drops a short distance before its weight is effectively sustained by the cushioning means. Such jolting of the load is undesirable and in some instances, disastrous, as, for example, where an elevating truck is employed to transport a platform supporting freshly moulded cement or concrete blocks, or where used to transport other semi-plastic or fragile materials.

The object of the present invention is to provide an elevating truck of the character described with mechanism for locking the load supporting means in elevated position adapted to impose a tension upon the locking means which will tend to unlock the same upon removal of the weight of the load supporting means from the locking mechanism, thus permitting the load supporting means to be lowered upon the cushioning device under the control of the operator.

In elevating trucks of this character means are usually provided for releasing the elevating means after the load supporting means has been raised to, and locked in, a predetermined position.

A further object of the invention is to provide means for preventing disengagement of the elevating means or which will compel re-engagement of the elevating means, so that the load supporting means will be under the control of the elevating means, before the locking means can be released, thus necessitating transfer of the weight of the load supporting means to the cushioning means under the control of the elevating means.

A further object of the invention is to pro-

vide an elevating truck embodying the aforesaid improvements which will be of rugged construction adapted to withstand hard usage and which will be certain in its operation so that accident to the load, by careless dropping thereof, will be effectively eliminated.

Other objects and features of the invention will more fully appear from the following description and the accompanying drawings, and will be particularly pointed out in the claims.

In the drawings:

Fig. 1 is a view, partially in longitudinal vertical section, of the preferred form of elevating truck embodying the invention;

Fig. 2 is an enlarged detail view illustrating particularly the position of the foot lever operable to impose a tension upon the locking dog;

Fig. 3 is a detail side elevation showing a portion of the locking dog, a spring connected thereto and a lever operable to place a tension upon the dog; and,

Fig. 4 is a detail view, partially in section, showing the interengaging pawl and ratchet forming part of the mechanism for lifting the load supporting means, after such further elevation of the load-supporting means.

A preferred embodiment of the invention is disclosed herein as applied to an elevating truck of the type illustrated and described in Letters Patent No. 1,445,838 granted February 20, 1923 to the Lewis-Shepard Company assignee of Ralph M. Lovejoy. The construction of the truck illustrated herein is substantially identical with that illustrated in the aforesaid Letters Patent. The frame of the truck comprises side rails 1, preferably of angle iron, connected together at the front end of an arched girder 2 having a central cylindrical boss 3 in which a steering post 5 is mounted which is provided with downwardly extending arms 4 having journals for the axle 5 of a steering wheel 6. The upper end of the steering post has secured to it and resting upon the upper end of the boss 5 a split collar 7 which is clamped upon the steering post by a bolt 8. This collar has upwardly and forwardly extending arms 9 having bosses 10 near their upper ends in which is journalled the pivoted shaft 11 of a vertical swinging tongue. The particular form of tongue shown in the drawings comprises a section of pipe 12, of any desirable length,

having a head 13 secured thereto and provided with suitable handles 14. The opposite end of the tubular portion of the tongue is seated in a socket in the cylindrical portion 5 15 of a lever which is pivoted upon the shaft 11 and is provided with an extension 16 shown in dotted lines in Fig. 1 which projects over the vertical steering post.

A vertical strut 17 is pivotally connected 10 to the extension 16 of the tongue and extends upwardly substantially in alignment with the axis of the steering post and is connected at its upper end by a swivel joint 18 to suitable lever mechanism for raising the load 15 supporting means. By reason of the fact that the strut 17 extends in substantial alignment with the axis of the steering post it will be obvious that the vertical swinging movement of the tongue may be utilized to actuate 20 the elevating mechanism when the tongue is in any steering position.

The rear ends of the side bars 1 of the main frame have secured to them brackets 19 which are provided with journals for a 25 shaft 20 upon which the rear wheels 21 of the truck are mounted.

The load supporting means illustrated herein is in the form of a platform comprising side bars 22, preferably of angle iron, a 30 connecting rear plate 23 and front standards 24 connected by suitable transverse members 25. The front end of the load supporting means is supported by lever mechanism comprising a lever 26 having a flat web-like construction with journals adjacent its ends which are pivotally mounted respectively upon shafts 27 and 28, the shaft 27 being mounted in brackets 29 carried by the side frames 1 and the shaft 28 in suitable bosses 35 40 in the lower portion of the standards 24. The lever member 26 has a central web 30 which extends forwardly and is pivotally connected at its front end to the lower end of an upwardly extending link 31, the upper end of 45 which is connected by a pin 32 to a sector-shaped lever 33 which is fulcrumed upon a shaft 34 mounted in the upper ends of the standards 24. A lifting lever 35, which is pivotally mounted upon the same fulcrum 50 shaft 34, extends forwardly over the axis of the steering post and is connected by the swivel 18 to the upper end of the strut 17. The sector-shaped lever 33 is provided with a series of teeth 36 which are adapted to be 55 engaged by a dog 37 having a pivotal shaft 38.

Suitable locking mechanism is provided to co-operate with the pawl and ratchet mechanism of the lifting device so that when the lifting lever 35 is raised and lowered by 60 the swinging movement of the tongue the dog 37 will engage successively the teeth 36 upon the sector lever 33. The dog 37, however, is provided with a notched end 39 which will engage the lowermost tooth 40 and prevent 65 the dog from dropping by gravity out of en-

gagement with the sector lever until the weight of the load supporting means is supported upon the dash pot or other means for cushioning the descent of the load supporting means as will hereinafter more fully appear. 70

The rear end of the load supporting means 22 is raised and lowered by means of toggle mechanism. The particular construction illustrated herein comprises toggle links 41 and 42 connected together at their adjacent ends by a shaft 43 and at their remote ends provided with pivotal connections 44 and 45 to the platform and the bracket 19 in which the rear axle 20 is journalled. The lever 26, for lifting the front end of the platform, has a 75 rearward and downward extension 46 to the end of which a link 47 is connected, the opposite end of said link being pivotally connected in turn to a link 48 which in turn is pivotally connected at its other end to the shaft 43 of the knee of the toggle. The arrangement desirably is such that when the platform is in lowered position, as illustrated in Fig. 1, the link 48 will rest upon and extend downwardly and rearwardly from the 80 shaft 20 so that upon forward movement of the link 27 the shaft 20 will act as a fulcrum to raise the knee of the toggle and thereby materially aid in the straightening movement of the toggle which is produced by further 85 forward movement of the link 48.

In the operation of the elevating mechanism, therefore, the vertical swinging movement of the tongue raises the lifting lever 35 and through the pawl 37 raises the sector lever 32. The movement of this lever, acting through the link 31, rocks the lever 26, which supports the front end of the platform, about its fulcrum 27 thereby lifting the front end of the platform through the shaft connection 105 28 thereto. The upward movement of the front end of the lever 26 causes downward movement of its rearward extension 46 which draws the link 47 forwardly, thereby 110 acting to straighten the toggle which supports the rear end of the platform. Thus the platform is raised vertically without substantial movement longitudinally of the frame of the truck.

The means for cushioning the descent of the load illustrated herein is in the form of a vertical dash pot 49 which is pivotally mounted at its lower end upon a bracket 50 carried by a transverse girder 51 which rests upon the side frames 1. The piston rod 52 115 of the dash pot is pivotally connected to an arm 53 which in turn is connected to the vertical link 31. The dash pot may be of any suitable type which permits a free flow of the liquid from the upper portion of the cylinder 120 by or through the piston to the lower portion of the cylinder during the upward movement of the piston with means for restricting the flow of fluid from the lower portion of the cylinder by or through the piston during 125 130

descent of the load. The dash pot desirably, however, is so constructed that the liquid will exert a resistance to the descent of the platform substantially proportionate to the weight of the load so that the platform will descend at substantially the same speed under different loads.

The mechanism thus described is substantially the same as that illustrated in the patent above mentioned.

The present invention relates particularly to locking mechanism for retaining the load supporting means in a predetermined elevated position which may be released to permit the descent of the load, but which may be only released after the weight of the load has been imposed upon the elevating mechanism. In the preferred construction illustrated the locking means comprises a ratchet 54 which may be secured to or made integral with the link 31 and which is provided with teeth complementary to the teeth 36 of the lifting sector 33. A suitable locking dog 55 cooperates with the ratchet 54 and means are provided which may be caused to impose a tension upon the dog, when the dog is in engagement with the ratchet and sustaining a part of the weight of the load supporting means, which will withdraw the dog from locking position upon removal of the weight of the load upon the dog.

In the preferred construction illustrated the dog 55 is secured to a rearwardly inclined arm or lever 56 which is pivotally mounted at its lower end upon a pin 57 carried by a bracket 58 which is supported upon the cross girder 51. The arm 56 normally tends to hold the dog in a position to engage the teeth 54 of the ratchet. Desirably a helical spring 59 secured at its upper end to a pin 60 on the sector lever 33 and at its lower end to a pin 61 upon the dog, insures normal engagement of the dog and ratchet. The means for imposing a tension upon the dog tending to release the dog from the ratchet when it is supporting a portion of the load comprises a helical spring 62 which may be conveniently connected to the same stud 61 upon the arm or lever 56 and which is connected at its other end to an extension 63 of a foot lever 64 which is pivotally mounted upon a shaft 65 in the ears of a bracket 66 which is secured to the web 67 of a transverse front arch-shaped member of the main frame. The foot lever 64 is provided with stop shoulders 68 and 69 to limit its forward and rearward movements. The lateral extension or stud 63 upon the lever 64 is so located that when the foot lever is in vertical position, illustrated in full lines in Fig. 1, and in dotted lines in Fig. 3, the spring 62 will not be under any substantial tension. When, however, the foot lever is swung forwardly and downwardly to the position illustrated in full lines in Fig. 3 a considerable tension will be imposed upon

the spring 62 which will tend to draw the dog 54 out of engagement with the ratchet. Furthermore, when the foot lever is moved to the operative position illustrated in Fig. 3 a plane, extending through the axis of the stud 63 and the stud 61 upon which the respective ends of the spring are connected, will lie beneath the axis of the pin or shaft 65 upon which the lever 64 is fulcrumed so that the shoulder 68 will be drawn firmly against the web 67 and the spring locked in tense position.

In the operation of the device the downward and upward swinging movements of the tongue cause the pawl 37 progressively to engage the teeth 36 of the sector 33, thus raising the sector and through the link 31 causing the lever 26 to raise the front end of the platform, while the toggle joint mechanism raises the rear end of the platform.

During the lifting of the load supporting means thus step by step the dog 55 engages the successive teeth of the ratchet 54. When the lowest tooth 70 of the ratchet is engaged by the dog 55 the dog 37 of the lifting lever 35 tends to swing from beneath the lowest tooth 40 of the sector 33, but is prevented therefrom as the notch 39 upon the tooth will engage the point of the tooth 40 when the tongue is raised to its uppermost position. Furthermore the dog 37 cannot be released from the sector 33 because further lifting of the load supporting means would find no corresponding tooth in the ratchet 54 with which the dog 55 might engage. The inter-engaging members of the lifting mechanism are prevented from disengagement until the sector 33 is raised by a downward movement of the tongue and the load lifted. The locking dog can then be removed and the load lowered until it is sustained by the dash pot, after which an upward movement of the tongue will permit the end of the dog to drop by gravity beneath the tooth 40 of the sector. Such upward movement of the tongue should be a quick movement. Otherwise the cushioning action of the dash pot might be sufficiently rapid to prevent the dog 37 from being released from its engagement with the tooth 40 of the sector.

During the lifting of the load supporting means the foot lever 64 is permitted to remain in vertical position, shown in Fig. 1, in which position no tension is imposed upon the spring 62 so that the dog 55 is held in engagement with the teeth of the ratchet 54 by gravity and also by the action of the spring 59. When, however, the load supporting means is locked in elevated position and the locking means retained in such position by the weight of the load, the foot lever 64 may be depressed into the position illustrated in full lines in Fig. 3, thereby imposing a tension upon the spring 62 tending to withdraw the lever 56 and its dog 55 from engagement with the teeth of the ratchet 54.

When the load has reached its destination the lowering of the tongue will raise the lifting lever 35 and its sector 33 sufficiently to transfer the weight of the load from the locking mechanism to the lifting lever 35. Thereupon the spring 62 will withdraw the dog 55 from engagement with the teeth of the ratchet 54. As the plunger 52 of the dash pot is connected to the lifting link 31, a slight upward movement of the tongue will transfer the weight of the load then sustained by the lifting lever 35 to the dash pot, and a further quick upward movement of the tongue will permit the notched end of the pawl 37 which forms a detachable connection with the load supporting means to drop out of engagement with the tooth 40 of the sector so that the load supporting means will be free to descend under the cushioning action of the dash pot.

It will thus be obvious that the weight of the load supporting means is transferred from the locking device to the dash pot under the control of the elevating mechanism and during such transfer the load is under the control of the operator and may be gently deposited upon the dash pot without jolting of the load. By reason of the construction described, therefore, a gentle lowering of the platform is insured which will substantially prevent injury to, or breakage of, objects or material resting upon the load supporting means during the lowering of the load supporting means.

It will be understood that the embodiment of the invention disclosed herein is of an illustrative character and is not restrictive and that various changes in form, construction and arrangement of parts may be made within the spirit and scope of the following claims.

Having thus described the invention, what is claimed as new, and desired to be secured by Letters Patent, is:

1. In an elevating truck comprising load supporting means and mechanism for elevating the load and means for cushioning the descent thereof, mechanical means for holding the load supporting means in elevated position adapted to be retained in locking position by the weight of the load imposed thereupon, and manually operable means to impose a tension upon said locking means and acting to release the locking means only when the weight of the load is transferred to the mechanism for elevating the load.

2. In an elevating truck comprising load supporting means, means for elevating the same having a detachable connection therewith, means for cushioning the descent of the load supporting means, mechanical locking means for holding the load supporting means in elevated position adapted to be retained in locking position by the weight of the load, manually operable means for imposing an

unlocking tension upon said locking means operable to release the locking means only when the weight of the load imposed upon the locking means is transferred to the elevating means, and means for retaining said elevating means in detachable connection with said load supporting means until said weight is transferred therefrom to said cushioning means.

3. In an elevating truck comprising load supporting means, releasable means for elevating said load supporting means, locking means for holding the load supporting means in elevated position and means for cushioning the descent of the load upon release of said locking means; means operable when the load supporting means is locked in a predetermined elevated position to impose a tension upon said locking means tending to unlock the same, whereby upon further elevation of said load supporting means the locking means will be rendered ineffective, and means for retaining said elevating means in detachable connection with said load supporting means until the weight of the load supporting means is transferred therefrom to the cushioning means after such further elevation of the load supporting means.

4. In an elevating truck comprising load supporting means, releasable means for elevating said load supporting means, operable to raise the load supporting means, means including a dog operable to lock the load supporting means against descent, means for cushioning the descent of said load supporting means upon release of said locking means, a spring connected to said dog, manually operable means for imposing tension upon said spring when the dog is retained in locked position by the weight of the load supporting means, and means for retaining the elevating means in detachable connection with said load supporting means until the weight of the load supporting means is transferred to the cushioning means.

5. In an elevating truck comprising steering mechanism including a tongue mounted to swing vertically, load supporting means, releasable interengaging members connecting said tongue to said load supporting means and operable by the vertical swinging movement of said tongue when the same is in any steering position to elevate the load supporting means step by step, locking means for holding said load supporting means in elevated position and means for cushioning the descent of the load when released by said locking means; means operable when the load supporting means is locked in a predetermined elevated position to impose tension upon said locking means tending to unlock the same, whereby upon removal of the weight of the load supporting means from the locking means said locking means will be rendered ineffective, and means for retaining said in-

terengaging members in engagement until the weight of the load supporting means is transferred to the cushioning means.

6. In an elevating truck comprising load supporting means, steering mechanism including a tongue mounted to swing vertically, a lifting lever, means including an upwardly extending link connecting said lifting lever to said load supporting means operable by vertical swinging movement of the tongue to raise said load supporting means, a dash pot connected to said link operable to cushion the descent of the load, a locking dog, means on said link co-operating with said dog, a spring connected to said dog and a manually operable lever connected to said spring operable, when said dog is held in locked position, to impose and maintain a tension upon said dog tending to unlock the same, whereby the weight of the load may be readily transferred by vertical swinging movements of the tongue to the cushioning means without jolting the load.

7. In an elevating truck comprising load supporting means, steering mechanism including a tongue mounted to swing vertically, a lifting device comprising a lever having a toothed sector, means including a link connecting said lever to said load supporting means, a pawl co-operating with said toothed sector operable by the vertical swinging movement of the tongue and capable of swinging out of engagement with said sector when the load supporting means is supported above a predetermined height, a dash pot connected to said link operable to cushion the descent of the load, a ratchet on said link, a dog normally engaging said ratchet, a spring connected to said dog and a foot lever connected to said spring operable when said dog is retained in locked position by the weight of the load to impose a tension upon said dog tending to withdraw it from locking position.

8. In an elevating truck comprising load supporting means, steering mechanism including a tongue mounted to swing vertically, a lifting device comprising a lever having a toothed sector, means including a link connecting said lever to said load supporting means, a pawl co-operating with said toothed sector operable by the vertical swinging movement of the tongue and capable of swinging out of engagement with said sector when the load supporting means is supported above a predetermined height, a dash pot connected to said link operable to cushion the descent of the load, a ratchet on said link, a dog normally engaging said ratchet, a spring connected to said dog and a foot lever connected to said dog, when said dog is retained in locked position by the weight of the load, to impose a tension upon said dog tending to withdraw it from locking position, and means for retaining the pawl in engagement

with said sector until the load supporting means has been raised above the highest effective locking position of said dog.

9. In an elevating truck comprising load supporting means, steering mechanism including a tongue mounted to swing vertically, a lifting device comprising a lever having a toothed sector, means including a link connecting said lever to said load supporting means, a pawl co-operating with said toothed sector operable by the vertical swinging movement of the tongue and capable of swinging out of engagement with said sector when the load supporting means is raised above a predetermined height, a dash pot connected to said link operable to cushion the descent of the load, a ratchet on said link, a dog normally engaging said ratchet, a spring connected to said dog, a foot lever connected to said spring operable when said dog is retained in locked position by the weight of the load to impose a tension upon said dog tending to withdraw it from locking position, and said pawl having a notch adapted to engage the lowest tooth of the sector when the load supporting means is locked by engagement of the dog with the lowermost tooth of the ratchet, whereby further upward movement of said sector is necessitated to permit said pawl to drop by gravity out of engagement with said sector.

10. In an elevating truck, comprising a load supporting means and mechanism for elevating the load, and means for cushioning the descent thereof, mechanical means for holding the load supporting means in elevated position adapted to be retained in locking position by the weight of the load imposed thereupon, and manually operable means comprising a lever and a spring connecting said lever to the locking means, to impose a tension upon said locking means, and acting to release the locking means only when the weight of the load is transferred to the mechanism for elevating the load.

11. In an elevating truck, comprising load supporting means and mechanism for elevating the load, and means for cushioning the descent thereof, mechanical means for holding the load supporting means in elevated position adapted to be retained in locking position by the weight of the load imposed thereupon, and manually operable means to impose a tension upon said locking means, comprising a lever and a spring connecting said lever to said locking means, means to retain said lever in tension imposing position, said manually operable means being adapted to release the locking means only when the weight of the load is transferred to the mechanism for elevating the load.

12. In an elevating truck comprising load supporting means, means for elevating the same having a detachable connection therewith, means for cushioning the descent of the load supporting means, mechanical locking

means for holding the load supporting means in elevated position adapted to be retained in locking position by the weight of the load, manually operable means for imposing an 5 unlocking tension upon said locking means operable to release the locking means only when the weight of the load imposed upon the locking means is transferred to the elevating means, and means comprising a rack, 10 and a notched pawl in said elevating means for retaining said elevating means in detachable connection with said load supporting means until the load is transferred to the cushioning means, said pawl being thereafter 15 released.

13. In an elevating truck, comprising load supporting means, releasable means for elevating said load supporting means, locking means for holding the load supporting means in elevated position, and means for cushioning the descent of the load upon the release 20 of said locking means; means operable when the load supporting means is locked in a pre-determined elevated position to impose a tension 25 upon said locking means tending to unlock the same, whereby upon further elevation of said load supporting means the locking means will be rendered ineffective, and means comprising a rack and a notched pawl 30 in said elevating means for retaining said elevating means in detachable connection with said load supporting means until the load is transferred to the cushioning means, said pawl being thereafter released.

14. In an elevating truck comprising load supporting means, releasable means for elevating said load supporting means, operable to raise the load supporting means, means including a dog operable to lock the load 40 supporting means against descent, means for cushioning the descent of said load supporting means upon release of said locking means, a spring connected to said dog, manually operable means for imposing tension upon said 45 spring when the dog is retained in locking position by weight of the load supporting means, and means comprising a rack and a notched pawl in said elevating means for retaining said elevating means in detachable 50 connection with said load supporting means until the load is transferred to the cushioning means, said pawl being thereafter released.

15. In an elevating truck comprising steer-

ing mechanism, including a tongue mounted to swing vertically, load supporting means, 55 releasable and engaging members, connecting said tongue to said load supporting means, and operable by the vertical swinging movement of said tongue when the same is in any steering position to elevate the load supporting 60 means step by step, locking means for holding said load supporting means in elevated position, and means for cushioning the descent of the load when released by said locking means, means operable when the load 65 supporting means is locked in a pre-determined elevated position to impose tension upon said locking means tending to unlock the same, whereby upon removal of the weight of the load supporting means from the locking 70 means, said locking means will be rendered ineffective, and means comprising a rack and a notched pawl in said elevating means for retaining said elevating means in detachable connection with said load supporting means 75 until the load is transferred to the cushioning means, said pawl being thereafter released.

16. In an elevating truck, comprising load supporting means, steering mechanism, including a tongue mounted to swing vertically, 80 a lifting device comprising a lever having a toothed sector, means including a link connecting said lever to said load supporting means, a pawl cooperating with said toothed sector operable by the vertical swinging 85 movement of the tongue, and capable of swinging out of engagement with said sector when the load supporting means is supported above a pre-determined height, a dash-pot connected to said link operable to cushion the 90 descent of the load, a ratchet on said link, a dog normally engaging said ratchet, a spring connected to said tongue, and a foot lever connected to said spring operable when said dog 95 is retained in locked position by the weight of the load to impose a tension upon said dog tending to withdraw it from locking position, and means comprising a notch in said pawl for retaining said pawl in engagement with said sector until the load supporting means 100 has been raised above the highest effective locking position of said dog.

In testimony whereof, I have signed my name to this specification.

FREDERICK J. SHEPARD, JR.
